UNITED STATES PATENT OFFICE.

JOHN E. GARDNER, OF CHICAGO, ILLINOIS, ASSIGNEE, BY MESNE ASSIGNMENTS, TO
AUTOMATIC ELECTRIC INC., OF CHICAGO, ILLINOIS, A CORPORATION OF DELA-
WARE.

AUTOMATIC TELEPHONE SYSTEM.

Application filed October 17, 1921, Serial No. 508,351. Renewed June 5, 1926.

The present invention relates in general to automatic telephone systems, and is more particularly concerned with such systems as are usually installed in mercantile establishments and the like, and which are commonly known as private automatic exchanges.

More specifically, the invention relates to the provision of a new and improved transfer or passing call system. Heretofore passing call systems have been designed, but all of these had to do with the passing or transferring of the call from one subscriber to another in the private automatic exchange on an incoming call from the main to the branch exchange. The present invention provides means whereby in the case of an outgoing call from a subscriber in the private automatic exchange to a subscriber in the main exchange, the calling party may transfer the call to another subscriber in the branch exchange. This type of service is especially desirable in case of an executive who has his secretary or office boy set up his connection for him. When such employee has extended a connection to the desired called party, the call may then be extended or transferred to the executive.

There are other objects of the invention not now specifically mentioned, which together with the foregoing will be described fully hereinafter with reference to the accompanying drawings.

Referring now to the drawings comprising Figs. 1, 2, and 3, there is shown by means of the usual circuit diagrams an outgoing connection from a calling subscriber in the private automatic exchange to a subscriber in the main exchange through the line switch C and connector H.

Referring now more particularly to Fig. 1, there is shown a subscriber's substation A of the usual automatic type, the associated line of which terminates at the exchange in the individual line switch C.

The line switch C is of the usual Keith or plunger type whose function is to extend the associated line when calling, over the trunk line which has been pre-selected by the associated master switch. Line switch C in common with a plurality of other similar line switches has access to trunk lines extending to local connector switches. All line switches of the group are adapted to be controlled in their trunk selecting opera-

tion by a master switch such as the one shown at M. One of the local connectors to which the line switch C has access, is shown in the drawings at H.

The master switch M is of the usual solenoid type and as mentioned before maintains all the line switch plungers associated with an idle trunk line.

The connector H is a switch of the usual Strowger vertical and rotary type of mechanical construction. The wipers of this connector switch have access to 100 blank contacts, these being divided into ten levels with ten sets in each level. On the first nine levels the connector H has access to 70 ordinary subscribers' lines, which are similar to the one shown at A. On the tenth level, however, this connector has access to trunk lines extending to the main exchange and is capable of operating as a selector, 75 to select and connect with an idle one of these trunk lines. One of these trunk lines is shown in the drawings terminating in the bank contacts 175-178, inclusive. Associated with each one of the local connectors 80 is a small ten-point rotary switch. The rotary switch associated with the local connector H is shown at F, Fig. 3.

Rotary switch F is of the same general mechanical construction as that of the well-known rotary line switches; however, its circuits are so changed that it now operates as a finder switch, as will be described later.

The group of relays shown in the upper part of Fig. 3 are certain relays on the connector H which have not been shown included in the connector, in order to avoid too great complication of the circuits; however, it will be understood that in practice all these relays are mounted on the connector switch.

Having briefly described the apparatus shown in the drawings, its operation will now be described more in detail. For this purpose, it will be assumed that the subscriber at substation A desires to extend the connection to a subscriber in the main exchange. In order to do this, the subscriber will remove his receiver and operate his calling device for the digits of the desired called number in the usual manner, except that the digit 0 will be prefixed.

When the receiver is removed at the calling substation, a circuit is completed for the line relay 20 of the line switch C, over the 110

line conductors 11 and 12 in series. Relay 20, upon energizing, at its armature 30, completes a circuit extending from ground, by way of front contact and armature 30 through 5 the pull down winding of the coil 21, open main conductor 50, and thence to battery by way of armature 72 and its back contact. The pull down winding is energized over this circuit and, upon operating, attracts the 10 plunger arm 23 and the cut-off armature 24. By the operation of the plunger arm 23, the calling subscriber's line conductors 11 and 12 are extended by way of springs 42 and 43, 40 and 41, trunk conductors 67 and 15 64, to the lower and upper windings of the line relay 101 of the connector H.

Line relay 101 is immediately energized over the calling line loop, and at its armature 120 completes the circuit of the slow- 20 acting relay 102. The latter relay, upon energizing, at its armature 127, prepares the impulsing circuits of the connector H, and at its armature 126, places ground upon release trunk conductor 65', thereby establishing 25 a holding circuit for line switch C. This holding circuit may be traced from ground on release trunk conductor 65', springs 47 and 46, and thence through the holding winding 22 of the coil 21 to battery. 30 It will be noted that the cut-off armature 24 upon being attracted, opens the circuit of the slow-acting line relay 20. However, it will be understood that the relay 20 maintains its armature attracted until the above 35 traced holding circuit is completed. The branch of this holding circuit also extends by way of the private normal conductor 63 to multiple connected test contacts in the banks of the local connector switches, whereby 40 by the line of the calling substation is protected from intrusion in the usual manner. Another branch of this holding circuit extends by way of the springs 44 and 45 to the contact 79 in the master switch bank, whereby 45 the master switch is caused to rotate the plunger arms of all idle line switches into association with an idle trunk line. This trunk selecting operation will now be described briefly. 50 When ground is placed upon the master switch bank contact 79, a circuit is completed, if the master switch wiper is in engagement with this contact, extending from grounded bank contact 79, master 55 switch wiper 77, common segment of the master switch bank, conductor 81, back contact and armature 84, and thence through the upper winding of the starting relay 75 to battery. Relay 75, upon energizing, at 60 its armature 85 closes a circuit for locking magnet 86. Magnet 86 operates to withdraw the locking arm from the fan shaped segment, whereby the line switch plunger arms of master switch wipers are moved 65 under the influence of a spring (not shown)

into association with the next trunk line. If this trunk line is busy, the starting relay will be maintained energized and consequently the locking magnet will be held operated. The master switch will continue 70 to rotate until the master switch wiper engages the bank contact of a trunk line which is idle. Under these conditions the starting relay will be energized as will the locking magnet, thereby allowing a locking arm to 75 engage the locking segment of the master switch, and thus stopping its rotation. Should the master switch rotate until its wipers are in engagement with the last 80 trunk line, the spring 93 will be operated 85 into engagement with its working contact and the trip relay 90 will be energized. The latter relay, upon operating, closes the circuit of the solenoid S, and also a locking circuit for the starting relay 75. The solenoid operates to rotate the line switch plunger arms, master switch wipers opposite the first trunk line. During the time which the master switch is rotating from the last 90 to the first trunk line, the armature of the trip relay 90 is held in an operated position by the spring 95, and consequently the master switch does not test for an idle trunk line. When opposite the first trunk line, the spring 95 is forced out of engagement with 95 the armature of the trip relay 90, and the trunk selecting operation of the master switch takes place in the same manner as was before described.

Returning now to the operation of the connector H, it will be noted that the circuit of the line relay 101 includes a secondary winding of the transformer of the tone machine T. This, of course, gives the calling subscriber a signal and notifies him that everything is in readiness for him to operate his calling device. By the operation of the calling device ten interruptions are produced in the line circuit of the line relay 101, which retracts its armature a corresponding number of times, each time sending an impulse of current over the following path: ground by way of armature 120 and its back contact, armature 127 and its front contact, off-normal springs 119 and 117, through the winding of the slow-acting low resistance relay 103, and thence through the winding of the vertical magnet 113 to battery. The above is the circuit over which the first impulse through the vertical magnet is sent. However, upon the first vertical step of the switch shaft, the off-normal springs are shifted and the remaining vertical magnet impulses traverse a new circuit 110 which is the same as the one previously traced, except that it includes the off-normal springs 119 and 118, and armature 129 and its front contact, relay 103 being now in an operated position. Magnet 113 operates to 115 raise the switch shaft carrying the wipers 120 125 130

170-173, inclusive, step by step until these wipers are placed opposite the tenth level of bank contacts. When the switch wipers are placed opposite the tenth level of bank contacts, the shaft springs 160 and 161 are operated into engagement with their working contacts, and the shaft spring 115 is forced out of engagement with its resting contact. A circuit is now completed which extends from ground on release trunk conductor 65', spring 162 and its working contact, spring 161 and its working contact, spring 114 and its resting contact, armature 128 and its front contact, back contact and armature 116 and through the winding of the relay 107 to battery. Relay 107, upon energizing, establishes a locking circuit for itself, and closes the circuit of the rotary magnet. The rotary magnet operates to rotate the switch wipers another step into engagement with the next set of bank contacts in the tenth level and at the same time opens the circuit of the test relay 107. The alternate operation of the test relay 107 and the rotary magnet 112 will continue until the switch wipers are rotated into engagement with an idle trunk line, which, we will assume is the trunk line terminating in bank contacts 175-178, inclusive. When the switch wipers are rotated into engagement with this set of bank contacts, there will be no ground potential present upon the test contact 176 engaged by the test wiper 171, and there will be no circuit completed for test relay 107. Thus, following the deenergization of the slow-acting relay 108, a circuit is completed which extends from ground on release trunk conductor 65', spring 162 and its working contact, armature 140 and its back contact, through the lower winding of the switching relay 109, back contact and armature 145, normally closed springs controlled by armature 150, test wiper 171, test contact 176 and through the resistance R to battery. Relay 109 is energized over this circuit and, upon operating, establishes a locking circuit for itself at its armature 149, places direct ground upon the test contact 176 at armature 150, opens the rotary magnet circuit at armature 151, removes the trunk tone connection from the winding of line relay 101, connecting ground thereto, and at armatures 148 and 155 completes a certain repeating circuit which will now be described.

It will be noted that there is a bridge across the trunk conductors 199 and 200 which includes an armature on the line relay 101 and which may be traced as follows: trunk conductor 199, bank contact 175, wiper 170, front contact and armature 148, armature 134 and its front contact, armature 144 and its back contact, through the upper winding of relay 104, armature 132 and its front contact, front contact and armature 133, through the lower winding of relay 104, front contact and armature 123, conductor 213, lower winding of the electropolarized relay 251, conductor 214, front contact and armature 136, armature 155 and its front contact, wiper 173, bank contact 178, to trunk conductor 200. By this bridge across the trunk conductors, a circuit is completed for the line relay of the incoming switch in the main exchange. Should this be a line switch, the trunk line will be extended to an idle first selector switch in the main exchange. If it is an incoming se-

130

lector, the line relay will be energized and will operate to close the circuit of its associated slow-acting release relay. As this bridge across the two trunk conductors 199 and 200 includes springs on the line relay 101 of the connector H, the calling subscriber at substation A by operating his calling device for various digits of the called number, controls the automatic switches in the main exchange in the usual manner, in order to extend the connection to the desired subscriber. When the calling device of the substation A is operated for the various digits, the slow-acting relay 108 is energized during each series of impulses, and operates to disconnect the impedance coil 104 from the bridge and closes the bridge direct across the trunk conductors through the springs on the line relay, in order to improve the impulse transmitting circuits.

It will be remembered that the above mentioned bridge includes the windings of the relay 104, and the lower winding of the 25 electropolarized relay 251. Relay 104 is energized in series with the line relays of the switches in the main exchange, but the electropolarized relay 251 is not operated at this time due to the current in both its 30 windings being in opposition.

When the called subscriber in the main exchange removes his receiver from the switch hook, the battery is reversed over trunk conductors 199 and 200, and the electropolarized relay 251 operates. Relay 251, upon energizing, at its armature 258 prepares a circuit of the relay 252, at its armature 257 prepares a point in the circuit of relay 250, at its armature 259 places ground upon conductor 208 for a purpose which will be described later, at its armature 261 places an additional battery connection upon the conductor 211, and at its armature 260 opens a point in the circuit of release magnet 111.

Should the calling subscriber desire to transfer the connection to another subscriber in the private automatic exchange, he will operate his calling device in accordance with the digits of that subscriber's number in the usual manner, except that the digit 1 is 50 prefixed.

When the calling device at substation A is operated in accordance with the digit 1, a single interruption is produced in the circuit of the line relay 101 which retracts its armature in response thereto. When the armature is retracted an impulse of current is sent over the circuit extending from ground by way of armature 120 and its back contact, armature 127 and its front contact, off-normal springs 119 and 118, armature 129 and its back contact, conductor 209, front contact and armature 258, and thence through the winding of relay 252 to battery. Relay 252, upon energizing, establishes a

locking circuit for itself at its armature 262, at its armature 264 completes a circuit of the line relay 271 of the finder switch F, and at its armature 263 completes a circuit which extends over the following path: ground by 50 way of armature 263 and its front contact, conductor 216, armature 154 and its front contact, wiper 172, bank contact 177, through the upper winding of relay 190, common conductor 193, back contact and armature 196 to battery. Relay 190, upon energizing, establishes a locking circuit for itself at armature 191 which includes the winding of the common relay 195, and at its armature 192 removes the ground connection from the test contacts, such as 294 in the banks of the finder switches in order to enable the trunk line to be connected with. The common relay 195, upon energizing, at its armature 196 disconnects battery from 85 the common conductor 193 so as to prevent any other subscriber operating a finder switch at this time, and thus causing interference as will appear later.

Returning now to the operation of the 90 finder switch, it will be remembered that a circuit was completed for line relay 271. Relay 271, upon energizing, at its armature 275 completes a circuit which includes the winding of the switching relay 272 and the 95 motor magnet 273 in series, and at its armature 276 connects the test wiper 293 to the above circuit at a point midway between the switching relay and the said motor magnet. If the wipers of the finder switch F are not 100 associated with the trunk line in use, there will be a ground potential present upon the test contact engaged by the test wiper 293. Switching relay 272 is short circuited and the motor magnet being supplied with direct ground by way of the said test wiper, will operate as a buzzer, and advance the switch wipers step by step in search of the trunk line with which the wipers of the connector switch H are now in engagement, and which is the trunk line shown in the drawings terminating in bank contacts 293-295, inclusive. When the switch wipers of the finder are rotated into engagement with this set of bank contacts, there will be no 110 ground potential present upon the bank contact 294, engaged by the test wiper 293, the rotation of the switch will cease, and the switching relay 272 being no longer short circuited will be energized in series with the motor magnet 273. Relay 272, upon operating, at its armature 279 completes the circuit of the release magnet 111, and at its armatures 277 and 291 establishes a new connection between the calling subscriber at 115 substation A, and the trunk line comprising conductors 199 and 200. The circuit of the release magnet 111 may be traced from ground by way of armature 274 and its front contact, armature 279 and its front contact,

120

125

130

conductor 206, off-normal spring 137 and its working contact, and thence through the winding of release magnet 111 to battery. Magnet 111 operates to restore the switch shaft carrying wipers 170-173, inclusive, to normal position.

At this point it would be well to mention the operation of the springs 162. These springs are a variety of off-normal springs, except that they are controlled directly by the vertical and release magnets, that is—as soon as the vertical magnet operates the spring 162 is forced into engagement with its working contact, and as soon as the release magnet operates, the spring 162 is forced out of engagement with its working contact. These springs may be attached to the double dog on any Strowger switch.

From the above, it will be apparent that as soon as the release magnet 111 operates to restore the switch shaft to normal, the ground is disconnected from the conductor 147', and the relays 109, 106, 105, 104, 252, and 251 are restored to normal. The de-energization of the relays 109, 106, 105, and 104 in the connector H serve to restore the circuits of the connector switch to normal, so that it may be re-operated. By the de-energization of relay 252, the circuit of the line relay 271 of the finder F is opened. The de-energization of the relay 251 serves to restore certain circuits to normal. When the connector switch H is released, the circuit of the relay 190 and the common relay 195 is opened, and these relays deenergize. Relay 195, upon deenergizing, serves to again connect battery to the common conductor 193, so that another subscriber may operate a finder switch. The de-energization of relay 190 serves to apply ground to the conductor 219, thereby establishing a holding circuit for the switching relay 272 of the finder switch F. It will be understood that this holding circuit is completed before the slow-acting line relay 271 has had time to deenergize. It will be noted that the relay 272, upon energizing, applies ground to the conductor 221 at armature 279' in order to maintain the outgoing trunk in use busy in the banks of the local connector switches.

When the calling subscriber at substation A operates his calling device for the first digit of the desired number, a series of interruptions is produced in the circuit of the line relay 101, which retracts its armature a plurality of times in response thereto. In response to the retractions of the line relay armature, the switch shaft of the connector H is raised step by step until the switch wipers 170-173, inclusive, are brought opposite the level of bank contacts corresponding to the digit dialled. The slow-acting relay 103 is energized in series with the vertical magnet of the switch during the vertical op-

eration, maintains its armature attracted 65 throughout the vertical movement of the switch, and at the termination thereof, de-energizes and transfers the impulsing circuit to the rotary magnet 112.

In response to the next and final digit of 70 the called number the line relay 101 retracts its armature a plurality of times. At each deenergization an impulse of current is sent over a circuit extending from ground by way of armature 120 and its back contact, 75 armature 127 and its front contact, off-normal springs 119 and 118, armature 129 and its back contact, normally closed springs controlled by armature 141, armature 151 and its back contact, and thence through the 80 winding of rotary magnet 112 to battery. Magnet 112, operates to rotate the switch wipers step by step until they are placed in engagement with the contact set associated with the desired line, and which we will assume are the bank contacts 184-187, inclusive. The slow-acting relay 108 is energized in multiple with the rotary magnet and operates to connect the test wiper 171 85 to the test relay 107. 90

It will first be assumed that the desired called line is busy. Under these conditions ground will be connected to the test contact 185 and the test relay 107 will be energized. Upon operating, relay 107 establishes a locking circuit for itself at armature 140, opens the rotary magnet circuit at armature 141, prepares the circuit for relay 253 at armature 142, and at armature 143 connects a lead from the busy machine to the lower 100 heavy talking conductor. In this manner, the calling subscriber is notified that the desired line is busy. Should the calling subscriber desire to call another party, he will operate his calling device for the digit 1, 105 which operation releases the connector H, and will thereafter dial the two digits of the desired number. 95

When the digit 1 is dialled, the line relay 110 retracts and attracts its armature once, in response thereto, thus sending an impulse of current over a circuit extending from ground by way of armature 120 and its back contact, armature 127 and its front contact, off-normal springs 119 and 118, armature 129 115 and its back contact, armature 142 and its front contact, conductor 215 and through the winding of the slow-acting relay 253 to battery. Relay 253 is energized over this circuit, and upon operating, completes a 120 circuit extending over the following path: ground by way of front contact and armature 269, armature 278 and its front contact, conductor 205, armature 122 and its front contact, off-normal spring 137 and its working contact, and through the winding of the release magnet 111 to battery. Magnet 111 operates in the same manner as before to 125

restore the switch shaft to normal and at the spring 162 to open the circuit of the relay 107.

By operating the calling device at substation A for two digits of the called number, the connector H may be re-operated into engagement with the called line in the same manner as was described before.

It will now be assumed that when the connector H is operated into engagement with the bank contacts 184-187, inclusive, that the associated line is idle. In this case there will be no ground potential upon the test contact 185 and relay 107 is not energized. Then, upon the deenergization of the slow-acting relay 108, a circuit is completed for the switching relay 109. In order to simplify the drawing as much as possible, the off-normals of the subscriber's line associated with the bank contacts 184-187, inclusive, have not been shown. However, it will be understood that the normals of this line are connected in the same manner as that of the calling substation A, the normals of this substation terminating in the bank contacts 179-182, inclusive. In order to facilitate the explanation, it will be assumed that the substation A is the called substation. The circuit of the relay 109 may then be traced from ground on release trunk conductor 65', spring 162 and its working contact, conductor 147', armature 140 and its back contact, through the lower winding of the switching relay 109, back contact and armature 145, normally closed springs controlled by armature 150, test wiper 171, test contact 180, private normal conductor 63, and thence through the winding 22 of the relay 21 in the line switch C to battery. The energization of the winding 22 serves to attract the cut-off armature 24, whereby the line of the called substation is disconnected from its normal battery and ground connections in the line switch associated with the called line.

In the connector H the relay 109, upon energizing, establishes a locking circuit for itself at armature 149, prepares the circuit for the relay 253 at armature 152, and at armatures 148 and 155 completes the ringing circuit. Ringing current is now intermittently projected out on the called line until the subscriber thereon responds. When this occurs, the ring cut-off relay 106 is energized over the called line loop. Relay 106, upon operating, establishes a locking circuit for itself at armature 135, at armatures 134 and 136 opens the ringing circuit, and at the front contacts of these armatures finally completes the talking connection. The relay 104 is immediately energized over the called line. Talking battery is supplied to the calling substation from the windings of the line relay 101 and to the called substation from the windings of the relay 104.

It will be noted that a circuit for feeding battery to the called line includes the lower winding of the electropolarized relay 251. The current in the lower winding of relay 251 is in such direction that it assists the upper winding and the relay armatures are attracted. The relay 104, upon energizing, at its armature 147 closes the circuit of the slow-acting relay 110 and at its armature 131 opens a point in the circuit of relay 250. The operation of relay 251 serves to prepare certain circuits, the functions of which will be described later.

The call having been passed to the desired party in the private automatic exchange, a three party conference may now be held between the two subscribers in the private automatic exchange and the subscriber in the main exchange.

The original calling subscriber may by operating his calling device for the digit 1, release the second called party in the private automatic exchange from the connection. When the digit 1 is dialled, the relay 252 is energized as before described, and closes the circuit of the release magnet 111 of the connector H. The connector H is then released in the same manner as was described before, and may be re-operated.

Should the original calling subscriber desire to retire from the connection, he may do so merely by replacing his receiver upon the switch hook. This operation causes the deenergization of relay 101, and the latter operation opens the circuit of the slow-acting relay 102. Relay 102, upon deenergizing, prepares a point in the release magnet circuit, and at armature 126 removes ground from the release trunk conductor 65', thereby opening the holding circuit of the calling line switch C, and allowing it to assume its normal position. After the deenergization of the line relay 101, and before the deenergization of the slow-acting relay 102, an impulse of current is sent to the slow-acting relay 253. Shortly after the deenergization of relay 102, relay 253 is deenergized. Ground is then replaced upon the release trunk conductor 65' and over the circuit extending from ground by way of front contact and armature 259, armature 268 and its back contact, back contact and armature 126 to release trunk conductor 65'. The ground on release trunk conductor 65' serves to maintain the connector switch H busy, so that it cannot be seized by another calling subscriber. The subscriber of the called substation in the private automatic exchange is still in communication with the called subscriber in the main exchange.

Should the called subscriber in the private automatic exchange find it necessary to transfer the call he may do so by prefixing the digit 1 to the number of the desired called party. When the digit 1 is dialled

the relay 104 retracts and attracts its armature. Relay 104, upon deenergizing, completes a circuit which extends from ground at armature 124 by way of back contact and armature 131, resting contact of shaft controlled spring 115 and the said spring, conductor 212, armature 257 and its front contact, upper winding of relay 250, common conductor 282 and thence to battery by way of armature 284 and its back contact. Relay 250, upon energizing, establishes a locking circuit for itself to ground on conductor 147 in series with the winding of common relay 280. Another result of the energization of relay 250 is that ground is removed from the trunk conductor 66 which extends to a bank contact in the auxiliary master switch bank associated with the trunk line connected to the connector H. Still another result of the operation of relay 250 is that a circuit for the release magnet 111 of the connector H is prepared at armature 256, and at the front contact of armature 255 a circuit is completed extending from ground thru armature 255 and its front contact, conductor 216, armature 154 and its front contact, wiper 172, bank contact 181, normal conductor 62 thru the pull down winding of the coil 21 of the line switch associated with the called line, common conductor 50 and armature 72 and its back contact to battery. However, this circuit is not effective at this time as the relay 87 is energized as will subsequently appear. It will be recalled that the locking circuit of the relay 250 included the winding of the common relay 280. Relay 280, upon operating, at its armature 284 disconnects battery from the common conductor 282 in order to prevent interference in passing the call and at armature 283 completes a circuit extending from ground by way of front contact and the said armature, conductor 204, conductor 70, and through the winding of the relay 76 to battery. Relay 76, upon energizing, at its armature 73 disconnects battery from all the line relays in the line switches of the group, at armature 84 disconnects the master switch 50 wiper 77 from the starting relay 75 and connects the auxiliary master switch wiper 78 thereto. As all the bank contacts of trunk lines are grounded in this bank except the trunk line associated with the connector H, ground having been removed from the bank contact of this trunk line by the operation of the relay 250, the master switch will then operate in the usual manner to select this trunk. Immediately upon so doing the open main relay 87 which was energized during the operation of the master switch deenergizes and again connects ground through the pull down winding of the line switches. As there is ground connected to the conductor 62 the pull down winding of

the coil 21 will immediately be actuated and the line switch of the called subscriber will be plunged in on the trunk line leading to the connector H. When this occurs a circuit is completed for the line relay 101 which immediately energizes and closes the circuit of the slow acting relay 102. There is another circuit completed by the energization of relay 101 which extends from ground by way of armature 120 and its front contact, conductor 210, armature 256 and its front contact, conductor 206, off-normal spring 137 and its working contact and thence through the winding of the release magnet 111 to battery. Magnet 111 operates to restore the switch shaft and the wipers of the connector H to normal at the same time opening the circuits of the relays 109, 106, 104, 250, 251 and 280. The deenergization of relays 109 and 106 serve to restore certain circuits in the connector H to normal. Relay 104, upon deenergizing, opens the circuit of the slow acting relay 110 which deenergizes removing ground from the conductor 65. The deenergization of relays 250 and 251 restore various circuits to normal. Relay 280, upon deenergizing, again connects battery to the common conductor 282 whereby a second call may be passed and opens the circuit of the relay 76 in the master switch M. The deenergization of relay 76 again connects battery to the line relay of the line switches and disconnects the auxiliary master switch wiper and again connects the wiper 77.

All the foregoing operations have occurred in response to the dialling of the digit 1 by the called subscriber in the private automatic exchange. These operations take an exceedingly short interval of time and the hunting operation of the master switch under the control of the auxiliary wiper 78 does not interfere with its regular operation of preselecting trunks.

The called subscriber in the private automatic exchange is now connected to the connector H and may now operate this connector in the same manner as before described to transfer the call to another private automatic exchange party. The call may be again transferred by that party in the same manner as was that just described.

It should be noted that immediately upon the line switch of the called subscriber plunging in on the trunk line leading to the proper connector switch the circuit of the line relay of that switch includes the secondary winding of the transformer of the tone machine. Consequently the called subscriber is notified when he may operate his calling device.

I claim:

1. In a telephone system, main and branch exchanges, telephone lines in both exchanges, automatic switches in both exchanges, trunk

lines extending from the branch to the main exchange, means controlled from a calling one of said telephone lines in said branch exchange for operating a series of said automatic switches to set up a connection with one of said telephone lines in said main exchange over one of said trunk lines, and automatic means controlled by said calling subscriber for then extending the connection 10 by automatic switches in the branch exchange to another called line in said branch exchange.

2. In a telephone system, telephone lines, main and branch exchanges, trunk lines connecting said exchanges, automatic switches in each exchange, means controlled from one of said telephone lines in said branch exchange for establishing a connection over one of said trunks by way of a series of 15 said automatic switches in said branch and main exchanges with one of said telephone lines in said main exchange, and means controlled from said calling line for operating some of said automatic switches in said 20 branch exchange in order to extend the said connection to a second one of said telephone lines in said branch exchange.

3. In a telephone system, telephone lines, main and branch exchanges, trunk lines connecting said exchanges, automatic switches in each exchange, means controlled from one of said telephone lines in said branch exchange, for establishing a connection over one of said trunk lines by way of a series 30 of said automatic switches in said branch and main exchanges with one of said telephone lines in said main exchange, means controlled from said calling line for operating some of said automatic switches in 35 said branch exchange in order to extend the said connection to a second one of said telephone lines in said branch exchange, and means controlled from the calling line for releasing the extended portion of the 40 connection.

4. In a telephone system, telephone lines, main and branch exchanges, trunk lines connecting said exchanges, automatic switches in each exchange, means controlled from one of said telephone lines in said branch exchange for establishing a connection over one of said trunk lines by way of some of 50 said automatic switches in said branch and main exchanges with one of said telephone lines in said main exchange, means controlled over the calling line for then extending the connection solely through some of 55 said branch exchange automatic switches to a second one of said telephone lines in said branch exchange.

5. In a telephone system, telephone lines, main and branch exchanges, trunk lines connecting said exchanges, automatic switches in each exchange, means controlled from one 60 of said telephone lines in said branch ex-

change for establishing a connection over one of said trunk lines by way of some of said automatic switches in said branch and main exchanges with one of said telephone lines in said main exchange, means controlled over the calling line for then extending the connection solely through some of 70 said branch exchange automatic switches to a second one of said telephone lines in said branch exchange, and means controlled from 75 the calling line for disconnecting the said calling line from the connection.

6. In a telephone system, telephone lines, main and branch exchanges, trunk lines connecting said exchanges, automatic switches 80 in each exchange, means controlled from one of said telephone lines in said branch exchange for establishing a connection over one of said trunk lines by way of said automatic switches in said branch and main exchanges with one of said telephone lines in 85 said main exchange, means controlled over the calling line for then extending the connection to another branch exchange line solely through some of said automatic 90 switches in said branch exchange, and means controlled from the calling line for disconnecting the said calling line from the connection while still maintaining a connection 95 between the two called telephone lines.

7. In a telephone system, telephone lines, main and branch exchanges, trunk lines connecting said exchanges, automatic switches in said branch exchange, means controlled from a calling one of said telephone lines 100 in said branch exchange for establishing a connection with one of said telephone lines in said main exchange through a series of said automatic switches, and means controlled from the said calling line for releasing part of said series of switches while still maintaining a connection with said called 105 telephone line.

8. In a telephone system, telephone lines, main and branch exchanges, trunk lines connecting said exchanges, automatic switches in said branch exchange, means controlled from a calling one of said telephone lines in said branch exchange for establishing a connection with one of said telephone lines in said main exchange through a series of 110 said automatic switches, and means controlled from the said calling line for releasing part of said series of switches while still maintaining a connection with said called telephone line whereby one switch of said series may be re-operated in order to extend 115 the connection to a second telephone line.

9. In a telephone system, telephone lines, main and branch exchanges, trunk lines connecting said exchanges, automatic switches in said branch exchange controlled from one of said telephone lines in said branch exchange for establishing a connection with 120 one of said telephone lines in said main ex- 125

change over one of said trunk lines, and means controlled from the said calling telephone line for releasing one of said automatic switches while maintaining a connection with said called telephone line.

10. In a telephone system, telephone lines, main and branch exchanges, trunk lines connecting said exchanges, automatic switches in said branch exchange controlled from one of said telephone lines in said branch exchange for establishing a connection with one of said telephone lines in said main exchange over one of said trunk lines, and means controlled from the said calling telephone line for releasing one of said automatic switches while maintaining a connection with said called telephone line, whereby said switch may be reoperated to extend the established connection to a second of said telephone lines.

11. In a telephone system, telephone lines, automatic switches, means controlled from a calling one of said lines for operating a series of said switches in order to extend a connection to a called one of said telephone lines, and means controlled from the calling line for releasing part of said series of switches at the calling end thereof while maintaining a connection with the said called line via the remaining switches, whereby the connection may be extended to another of said telephone lines.

12. In a telephone system, telephone lines, automatic switches, means controlled from a calling one of said lines for operating a series of said switches to extend connection to a called one of said telephone lines, and means controlled from the said calling line for releasing and reoperating the first switch of said series while maintaining a connection with the said called line by way of the remaining switches.

13. In a telephone system, telephone lines, automatic switches, means controlled from a calling one of said lines for operating a series of said switches to extend connection to a called one of said telephone lines, and means controlled from the said calling line for releasing and reoperating one switch at the calling end of said series while maintaining a connection with the said called line by way of the remaining switches, whereby the established connection may be extended to include a second called one of said telephone lines.

14. In a telephone system, main and branch exchanges, subscribers' lines, trunk lines interconnecting said exchanges, means including an automatic switch having access to subscribers' lines and to trunk lines and controlled by a calling subscriber in said branch exchange for extending a call to a subscriber's line in said main exchange over one of said trunk lines, and means including an automatic switch having access

to trunk lines only and controlled from said calling line for them extending the connection to another called line in said branch exchange.

15. In a telephone system, telephone lines, main and branch exchanges, trunk lines connecting said exchanges, automatic switches in said exchanges, means controlled from a calling telephone line in said branch exchange for extending a call over one of said trunk lines by way of a series of automatic switches in said branch and main exchange to a telephone line in said main exchange, and means controlled from said calling line for operating an automatic switch to maintain said established connection while releasing one of the switches in said series in order to extend the said connection to a second one of said telephone lines in said branch exchange.

16. In a telephone system, telephone lines, main and branch exchanges, trunk lines connecting said exchanges, automatic switches in said exchanges, means controlled from a calling telephone line in said branch exchange for extending a call over one of said trunk lines by way of a series of automatic switches in said branch and main exchanges to a telephone line in said main exchange, and means controlled from said calling line for operating an automatic switch to seize the trunk line involved in said call in order to maintain said established connection while releasing one of the switches in said series in order to extend the connection to a second one of said telephone lines in said branch exchange.

17. In a telephone system, telephone lines, main and branch exchanges, trunk lines connecting said exchanges, automatic switches in said exchanges, means controlled from a calling telephone line in said branch exchange for extending a call over one of said trunk lines by way of a series of automatic switches in said branch and main exchanges to a telephone line in said main exchange, and means controlled from said calling line for operating an automatic switch to seize the trunk line involved in said call in order to maintain said established connection while releasing one of the switches in said series in order to extend the connection to a second one of said telephone lines in said branch exchange, said last extension being accomplished by reoperating said released switch.

18. In a telephone system, telephone lines, main and branch exchanges, trunk lines connecting said exchanges, automatic switches in said exchanges, means controlled from one of said telephone lines in said branch exchange for establishing a connection over one of said trunk lines by way of automatic switches in said branch and main exchanges with one of said telephone lines in said main

- exchange, means controlled over the calling line for then releasing one of said switches in said branch exchange while operating another automatic switch having access to 5 trunk lines only into connection with the trunk line involved in the call to maintain the established connection.
19. In a telephone system, telephone lines, main and branch exchanges, trunk lines connecting said exchanges, automatic switches in said exchanges, means controlled from one of said telephone lines in said branch exchange for establishing a connection over one of said trunk lines by way of automatic 10 switches in said branch and main exchanges with one of said telephone lines in said main exchange, means controlled over the calling line for then releasing one of said switches in said branch exchange while operating another 15 automatic switch having access to trunk lines only into connection with the trunk line involved in the call to maintain the established connection, and means for reoperating said released automatic switch 20 in order to extend the call to a second one 25 of said telephone lines in said branch exchange.
20. In a telephone system, telephone lines, main and branch exchanges, trunk lines interconnecting said exchanges, automatic 30 switches, means including an automatic switch having access to telephone lines and to trunk lines and controlled from a calling telephone line in said branch exchange for establishing a connection over one of said 35 trunk lines with one of said telephone lines in said main exchange, means controlled over the calling line and including an automatic switch having access to trunk lines only for 40 then extending the connection solely through some of said branch exchange automatic switches to a second one of said telephone lines in said branch exchange, and means controlled from the calling line for disconnecting 45 the said calling line from the connection.
21. In a telephone system, telephone lines, main and branch exchanges, trunk lines interconnecting said exchanges, automatic switches, means including an automatic 50 switch having access to telephone lines and to trunk lines and controlled from a calling telephone line in said branch exchange for establishing a connection over one of said trunk lines with one of said telephone lines in said main exchange, means controlled over 55 the calling line and including an automatic switch having access to trunk lines only for then extending the connection solely through some of said branch exchange automatic 60 switches to a second one of said telephone lines in said branch exchange, and means controlled from the calling line for disconnecting the said calling line from the connection while still maintaining a connection 65 between the two called telephone lines.
22. In a telephone system, telephone lines, main and branch exchanges, automatic switches in said branch exchange, means controlled from a calling one of said telephone lines in said branch exchange for establishing a connection with one of said telephone lines in said main exchange, said means including an automatic switch comprising two elements, one of said elements having access to telephone lines and to trunk lines, the other element having access to trunk lines only. 70
23. In a telephone system, telephone lines, main and branch exchanges, automatic switches in said branch exchange, means controlled from a calling one of said telephone lines in said branch exchange for establishing a connection with one of said telephone lines in said main exchange, said means including an automatic switch comprising two elements, one of said elements having access to telephone lines and to trunk lines, the other element having access to trunk lines only, and means controlled from said calling line for releasing part of said connection while still maintaining a connection with said called telephone line. 75
24. In a telephone system, telephone lines, main and branch exchanges, automatic switches in said branch exchange, means controlled from a calling one of said telephone lines in said branch exchange for establishing a connection with one of said telephone lines in said main exchange, said means including an automatic switch comprising two elements, one of said elements having access to telephone lines and to trunk lines, the other element having access to trunk lines only, and means controlled from said calling line for releasing part of said connection while still maintaining a connection with said called telephone line by way of said element having access to trunk lines only. 80
25. In a telephone system, telephone lines, main and branch exchanges, automatic switches in said branch exchange, means controlled from a calling one of said telephone lines in said branch exchange for establishing a connection with one of said telephone lines in said main exchange, said means including an automatic switch comprising two elements, one of said elements having access to telephone lines and to trunk lines, the other element having access to trunk lines only, and means controlled from said calling line for releasing part of said connection while still maintaining a connection with said called telephone line by way of said element having access to trunk lines only. 85
26. In a telephone system, telephone lines, automatic switches including a dual switch 90
- 95
- 100
- 105
- 110
- 115
- 120
- 125
- 130

comprising two independently operable elements, means controlled from a calling one of said lines for operating a series of said switches to extend connection to a called one of said telephone lines via one element of said dual switch, and means controlled from said calling line for releasing and reoperating said element while maintaining a connection with said called line by way of 10 said second element.

27. In a telephone system, telephone lines, automatic switches including a dual switch comprising two independently operable elements, means controlled from a calling one 15 of said lines for operating a series of said switches to extend connection to a called one of said telephone lines via one element of said dual switch, and means controlled from said calling line for releasing and reoperating 20 said element while maintaining a connection with said called line by way of said second element, the reoperation of said released element serving to extend the connection to a second called one of said telephone 25 lines.

28. In a telephone system, telephone lines, inter-office trunks, an automatic switch comprising two elements, the first element having access to telephone lines and to trunk 30 lines, the second element having access to trunk lines only, means controlled from a calling one of said telephone lines for operating said first element to extend a connection to a called one of said telephone lines 35 via one of said inter-office trunks, and means controlled from the calling line for releasing said first element and operating said second element into connection with said inter-office trunk to maintain the connection.

29. In a telephone system, telephone lines, inter-office trunks, an automatic switch comprising two elements, the first element having access to telephone lines and to trunk lines, the second element having access to 45 trunk lines only, means controlled from a calling one of said telephone lines for operating said first element to extend a connection to a called one of said telephone lines via one of said inter-office trunks, and means controlled from the calling line for releasing 50 said first element and operating said second element into connection with said inter-office trunk to maintain the connection, said released element being then available for further extensions.

30. In a telephone system, telephone lines, inter-office trunks, an automatic switch comprising two elements, the first element having access to telephone lines and to trunk lines, the second element having access to 55 trunk lines only, means controlled from a calling one of said telephone lines for operating said first element to extend a connection to a called one of said telephone lines via one of said inter-office trunks, and means

controlled from the calling line for releasing said first element and operating said second element into connection with said inter-office trunk to maintain the connection, said released element being then available 70 for further extensions under control of said calling telephone line.

31. In a telephone system, telephone lines, main and branch exchanges, trunk lines connecting said exchanges, a first automatic 75 switch in said branch exchange having direct access to trunk lines and to telephone lines, a second automatic switch auxiliary thereto and having access to trunk lines only, and means to prevent said second automatic 80 switch from seizing a trunk line unless said trunk line has already been taken into use in the extension of a call.

32. In a telephone system, telephone lines, main and branch exchanges, trunk lines connecting said exchanges, a first automatic 85 switch in said branch exchange having direct access to trunk lines and to telephone lines, a second automatic switch auxiliary thereto and having access to trunk lines only, and means to prevent said second automatic 90 switch from seizing a trunk line unless said trunk line has already been taken into use by said first automatic switch in the extension of a call.

33. In a telephone system, telephone lines, main and branch exchanges, trunk lines connecting said exchanges, a first automatic switch in said branch exchange having direct access to trunk lines and to telephone lines, 100 a second automatic switch auxiliary thereto and having access to trunk lines only, and means to prevent said second automatic switch from seizing a trunk line unless said trunk line has already been taken into use 105 from said branch to said main exchange.

34. In a telephone system, main and branch exchanges, subscribers' lines in said exchanges, trunk lines interconnecting said exchanges, a connector switch in said branch exchange comprising two elements, one element having access to said subscribers' lines and to said trunk lines, the other element having access to said trunk lines only, means for seizing said switch from a calling line 110 and for causing said first element to automatically select an idle one of a group of trunks, thereby forming a link in a call from said branch to said main exchange, and means controlled by said second element 115 controlled from said calling line for releasing said first element and for capacitating said first element to be thereafter operated by directive control of said calling line to extend said connection to another called line in said branch exchange.

35. In a telephone system, main and branch exchanges, subscribers' lines in said exchanges, trunk lines interconnecting said exchanges, a connector switch in said branch 125 exchange

exchange comprising two elements, one element having access to said subscribers' lines and to said trunk lines, the other element having access to said trunk lines only, means 5 for seizing said switch from a calling line and for causing said first element to automatically select an idle one of a group of trunks, thereby forming a link in a call from said branch to said main exchange, and 10 means controlled by said second element controlled from said calling line for releasing said first element and for capacitating said first element to be thereafter operated by directive control of said calling line to extend said connection to another called line in said branch exchange, said second element maintaining the continuity of said first established connection to said main exchange. 15

36. In a telephone system, subscribers' telephone lines, main and branch exchanges, trunk lines connecting said exchanges, a first automatic switch in said branch exchange having access to subscribers' telephone lines and to said trunk lines, an auxiliary automatic switch associated with said 20 first automatic switch and having access to said trunk lines only, means controlled from a calling one of said subscribers' lines in said branch exchange for operating a series 25 of automatic switches including said first

switch to extend a connection to a subscriber's line in said main exchange over one of said trunk lines, and means in said switches controlled by said calling subscriber 35 for then releasing said first switch while maintaining the connection over said second switch, and for operating said first switch into connection with another called line in said branch exchange. 40

37. In a telephone system, telephone lines, main and private automatic exchanges, trunk lines connecting said exchanges, an automatic switch in said branch exchange comprising two independently operable elements, one element having direct access to said telephone lines and to said trunk lines, the other element having access to said trunk lines only, subscriber controlled means for seizing said switch to extend a call via 45 said first element over a trunk line to a called line in said main exchange, and means controlled by said second element controlled from the calling line for releasing said first element and for capacitating said first element to be thereafter operated to extend the connection to another called line. 50

In witness whereof, I hereunto subscribe my name this 15th day of October, A. D. 1921.

JOHN E. GARDNER.
